FASTENING DEVICE FOR BADGES

William F. Ferguson, Yonkers, N. Y.

Application April 6, 1938, Serial No. 200,319

1 Claim. (Cl. 40—1.5)

This invention relates to fastening devices for badges and the like and particularly to devices for fastening a policeman's badge on his coat.

It is an object of the present invention to provide a device that will positively hold the badge on the coat.

Another object is to provide such a device that permits ready attachment and detachment of the badge on the coat.

Still another object is to provide such a fastening device that is simple in construction and economic to manufacture.

Other advantages of the invention will be apparent from the description thereof to follow taken in connection with the accompanying drawing in which—

Figure 1 is a rear view of a badge with one form of the invention mounted in position thereon.

Figure 2 is a side view of the badge and improved fastening device in position on a coat.

Figure 3 is a front view of the improved form of fastening device shown in Fig. 1.

Figure 4 is a detail view showing the arrangement of latch members and coil spring.

Figure 5 is a front view of another modified form of improved fastening device.

Referring to the drawing, a policeman's metal badge 10 of ordinary construction is illustrated.

The rear of this badge is provided as shown with a perforated ear or lug 11 at the top and bottom. These lugs 11 extend through spaced openings in a policeman's coat 12 to the rear of the coat as shown in Fig. 2. The regulation or standard coat of a policeman is formed with these spaced openings.

The improved fastening device comprises a tubular metal casing or housing 13. Slidably mounted in this housing is a latch member or bolt 14 having one end 15 protruding outwardly from one end of the housing. A finger piece 16 is formed on the bolt 14 adjacent its inner end and protrudes outwardly through an opening or slot 17 in the casing 13. A similar latch or bolt 18 is enclosed in the housing 13 but spaced from the first latch 14. This latch 18 has one end 19 protruding from the opposite end of the housing 13 and is also provided with a finger piece 20 protruding through the slot 17.

A coil spring 21 is positioned between the bolts 14 and 18 with one end surrounding the inner end of bolt 14 and seated against the finger piece 16 and its other end surrounding the inner end of bolt 18 and seated against the finger piece 20. This spring 21 normally presses the bolts 14

and 18 away from each other and presses the protruding ends 15 and 19, respectively, outwardly of the housing 13.

In use, the badge 10 is placed on the coat so that its perforated lugs 11 extend through the slits in the coat 12 to the rear surface thereof. The fastening device is then positioned between the lugs so that the protruding ends of the bolts 14 and 18 are in line with the openings in the lugs. This can readily be accomplished by grasping the finger pieces 16 and 20 and pressing them toward each other against the action of spring 21 so that the protruding ends 15 and 19 will be retracted toward the housing 13 and the overall length of the device shortened as will be understood, sufficiently to position it between the lugs. The finger pieces 16 and 20 are then released and the spring 21 will press the bolts 14 and 18 with their protruding ends 15 and 19, respectively, outwardly so that said protruding ends will extend through the openings in the lugs 11 and thus fasten or lock the badge on the coat. In order to remove the badge, it is only necessary to grasp the finger pieces 16 and 20 and press them toward each other until the protruding ends 15 and 19 are free of the lugs 11 when the device can be displaced and the badge removed from the coat.

In Figure 5 a slightly modified form of the invention is shown and consists of a housing 22 similar to the housing 13 of Fig. 1. In this form, the housing is provided with a protruding bolt or pin 23 which is fastened in the housing in any suitable manner, in one end thereof. A latch or bolt 24 is slidably mounted in the housing at the other end thereof and has one end 25 protruding from said end. A finger piece 26 is provided for the bolt 24 and protrudes through an opening or slot 27 in the housing. A coil spring 28 is positioned in the housing and has one end surrounding the inner end of bolt 24 and seated against the finger piece 26 and its other end is seated against the inner end of fixed pin 23 or may be seated against any stationary part of the housing 22. A bayonet slot 29 may be provided in the housing 22 to hold the finger piece 26 when it is in its innermost position as shown in dotted lines in Fig. 5.

In using the form of improved device shown in Fig. 5, the protruding pin 23 is first inserted into one of the lugs 11, preferably the lower one, and the other protruding end 25 of bolt 24 is retracted by pressing down on the finger piece 26 against the action of spring 28 and the end 25 then positioned in line with the opening in

the other or upper lug 11 when pressure is released on the spring forcing said end 25 upwardly through the lug 11 to fasten the badge on the coat.

- 5 Changes in details may be made without departing from the principle of the invention.

I claim:

- 10 In combination with a badge having spaced perforated lugs, a tubular casing having an opening at one end and a central slot, a protruding pin fixed in one end of the casing and forming a prolongation of said end, a bolt member slid-

ably mounted in the opposite end of the casing and having one end adapted to protrude through the open end of the casing, a finger piece secured to said bolt and protruding externally of the casing through the central slot and a coil spring 5 in the casing having one end seated against the inner end of the pin and its other end against the inner end of the slideable bolt, said central slot being formed with a notch for holding the finger piece in innermost position. 10

WILLIAM F. FERGUSON.
